UNITED STATES PATENT OFFICE

136,304

DESIGN FOR A SWING

William I. Smith, Goshen, Ind., assignor to The Hetrick Manufacturing Company, Toledo, Ohio, a corporation of Ohio

Application January 20, 1943, Serial No. 109,290

Term of patent 14 years

To all whom it may concern:

Be it known that I, William I. Smith, a citizen of the United States and a resident of Goshen, Elkhart County, Indiana, have invented a new, original, and ornamental Design for a Swing of which the following is a specification, reference being had to the accompanying drawings, forming a part thereof.

In the drawings:

Figure 1 is a perspective view of the swing, showing my new design; and

Figure 2 is a perspective view of the swing shown in Figure 1.

I claim:

The ornamental design for a swing, as shown.

WILLIAM I. SMITH.
